UNITED STATES PATENT OFFICE

IRA WALTON HENRY, OF GREENWICH, CONNECTICUT, ASSIGNOR TO IONIZING CORPORATION OF AMERICA, OF NEW YORK, N. Y., A CORPORATION OF NEW YORK

METHOD AND APPARATUS FOR TREATMENT OF HYDROCARBONS

Application filed August 15, 1929. Serial No. 386,182.

This invention relates to the conversion of hydrocarbonaceous starting material into hydrocarbonaceous vapors and liquids of changed molecular weights; method and apparatus.

One of the advantages and objects of the invention is production of anti-knock gasoline.

By starting material is meant that material or matter which is initially treated. Such starting material includes crude petroleum, natural gas, coal, lignite, shale, shale oil and other hydrocarbonaceous material of a bituminous nature. The applicability of the present invention is herein described with more particular reference to the conversion of crude petroleum oil, as starting material, into products of changed molecular weights; that is, of molecular weights differing from the molecular weight of the oil itself.

In my United States Patent No. 1,601,213 of September 28th, 1926, I described and claimed among other features,—The method of producing hydrocarbons possessing properties similar to those of benzol, consisting in subjecting bituminous material, in a place of partial confinement, to heat in a high frequency, oscillating electric field, vaporizing and decomposing the hydrocarbons of said bituminous material while subjecting the resulting products to the action of hydrogen gas for conversion into the desired products.

In my subsequent United States Patents 35 Numbers 1,709,813; 1,709,814 and 1,709,815, all of April 16, 1929, I described various methods and apparatus for converting petroleum oil and other hydrocarbonaceous starting material into desired products, 40 either unfinished as in the case of hydrocarbon vapors; or finished, as in the case of gasoline, for example; and the general object of the present invention is to improve upon my prior inventions and to produce apparatus and methods for economic betterment of the procedure indicated in my said patents and for betterment of the quality of the hydrocarbon products obtained by it.

In all cases, I have heretofore shown and now show a high frequency, oscillating, non-

discharging and consequently non-sparking electromagnetic field in which the starting material to be converted is treated. Such electromagnetic fields possess the function of dissociating the hydrocarbonaceous starting 55 into hydrogen and carbon, electrifying the carbon molecules, and of primarily forming a hydrocarbon vapor of hydrogen and exceedingly small electrified carbon particles; involving what is often referred to as ionization.

It is well known that crude petroleum from different fields and different countries varies in quality. For example, some Texas fields yield crude petroleum containing so much sulphur that such oils have been deemed impossible of refining except at a prohibitive cost.

Generally, the differing hydrocarbonaceous starting materials convertible by my invention are so variable that some are best treated under partial vacuum; others under low pressure; some under high pressure; and some at low; others at intermediate, and some under high temperatures.

In some cases, it is preferred to treat the starting material in batches; in other cases, the starting material is best fed to the high frequency, oscillating, electromagnetic field continuously, depending on circumstances. 80 Again, it is often desired to convert the starting material not into products of lighter molecular weight, as in the case of benzol, gasoline and the like, but on the contrary, into some product of heavier molecular weight, 85 such as lubricating oil, for example.

I have discovered a hitherto unknown and unsuspected waxy content or substance in my gasoline distillate and which up to this time has defied chemical analysis; and which 90 has previously gone over into the finished product wherein, when that product has been used as fuel for internal combustion engines, such waxy substance has been promotive of carbonization of engine cylinders and pistons. By my present invention such deleterious waxy substance is removed from the distillate, the quality of which is thereby improved.

As another instance of the practical ob-

jects and advantages of this invention, I point out that whereas, in converting hydrocarbonaceous starting material into vapors, in a high frequency, oscillating, non-discharging and consequently non-sparking electromagnetic field, it has always been heretofore deemed necessary to employ a chambered converter, receiver, container or still of dielectric material, such as ceramic or 10 pyrex glass which are of low tensile strength, I have discovered how to generate such a field in a chambered converter, receiver or the like, made of metal having high tensile strength, such as steel for example. This 15 is a reversal of all prior knowledge on that point, but does not mean that dielectric receivers are in all cases to be displaced when used in association with alternating electric current coils effective to generate high frequency, oscillating, non-discharging, non-sparking electromagnetic fields. But it does mean that for the first time I now provide the art, and that by my invention the art is provided, with a metal, chambered converter 20 which can be used for high internal pressure work when and if such high pressure operation is desired with safety to property and life, in the case of installations containing the kind of electric field specified.

Such a field is wholly different from a high tension electric condition producible within the chamber of a metal converter through which chamber a high tension alternating electric current conductor extends, 30 with such a conductor electrically insulated from the metal wall of the receiver. By such a structure, a high tension electric condition is established around the conductor and between it and the encasing metal of the receiver, and electrical discharges both audible and silent of high tension are set up from the conductor to the metal wall. Such discharges, however, have been found, as is well known in the art of installing high tension 35 feed wires and the like on petticoat insulators, for examples, to result in such violent sparking that loss of life has frequently occurred. Such discharges though creating high tension and oscillating fields, under 40 the conditions mentioned, would inevitably result in sparking and explosions if hydrocarbonaceous material were passed into the receiver for treatment.

The high frequency, oscillating, non-discharging and therefore non-sparking electromagnetic field which I employ cannot be generated except as the result of a high frequency, alternating electric current through an electric conducting coil. In 45 other words, the field in which I treat hydrocarbonaceous starting material is the function of a coil energized by a high frequency, alternating electric current through the coil as a conductor.

High frequency, oscillating, non-discharg-

ing, non-sparking electromagnetic fields as heretofore generated by different existing types of alternating current generators as made for the market have had the hitherto unperceived objection of not providing 50 means for change of frequencies; and I have discovered that, in the conversion of hydrocarbonaceous starting material into vapors or liquid products, better and purer qualities thereof are obtained by converting the 55 starting material in a high frequency, oscillating, non-discharging, non-sparking electromagnetic field in which the frequency of the oscillations is regulated and constantly and certainly maintained for the different 60 qualities and characters of the particular starting materials under treatment at a given time; changing the frequencies to suit the so-called natural periods of the different kinds or qualities of the crude petroleum or other 65 hydrocarbonaceous starting materials converted. I hereinbelow describe one form of apparatus effective for that purpose and by which selected, different constant frequencies of oscillation can be effected for different 70 grades or kinds of starting material.

It may be emphasized that the herein described metallic converter of high tensile strength to meet high pressure conditions may constitute a standardized converter for 75 use at all pressures whether above or below atmospheric pressure; but many of the herein described chamber members may be of ceramic material.

An important feature of this invention 800 relates to the recovery and introduction into a final product of the light fixed hydrocarbon gases which have hitherto either gone to waste or been burned under boiler furnaces or the like.

Another important feature of the invention relates to the conversion of said starting material into hydrocarbon vapors and liquids of changed molecular weight by dissociation of the starting material in exclusion 850 from extraneous oxygen and without addition or use of hydrogen obtained from any source extraneous to the starting material itself.

Another feature provides for effective and economic low temperature conversion of the starting material into hydrocarbon vapors and liquids.

The foregoing is a statement of some of the objects and advantages of my present method and apparatus, other features of the invention being set forth hereinafter.

In the accompanying drawings forming a part hereof, and illustrating now preferred apparatus forms of my invention, and showing forms thereof useful in practicing my new method:

Fig. 1 is a view, partly in diagram, partly in side elevation and partly in vertical, sectional elevation of a steel converter having an

interior, electrically insulated field generating coil of catalytic metal; and shows a partial vacuum system for treatment of crude petroleum; the apparatus being provided 5 with my new alternating current generator for effecting either variable or constant frequency of oscillations in the electromagnetic field transversely and throughout the length of the coil. The vacuum apparatus shown 10 is convertible, at the will of the operator, into a pressure system.

Fig. 2 is a view similar to that of Fig. 1 with the partial vacuumizing apparatus omitted.

15 Fig. 3 is a transverse horizontal section at line 3—3 of Fig. 1 illustrating the catalytic cylinder structure shown in Figs. 1 and 2. Figs. 4 and 5 show modifications.

It is noted that the partial vacuum apparatus shown in the drawings is of the barometric type and capable of producing a partial vacuum of from about twenty-seven inches to twenty-eight inches of mercury.

In the Fig. 1 form of apparatus, an oil 25 supply pipe 1 leads to the intake side of an oil charging pump 2 which discharges through a pipe 3 into the upper part of the chamber of a steel walled converter 4. If preferred, the starting material may be fed 30 into the converter by gravity, in some cases; but the use of a feed pump the speed of which may be varied from negligible head to high pressure of the starting material fed is desirable as explained below.

35 The lower portion of the chamber of the converter, which may be called a receiver, or a container, or a still, is provided with an interior, tubular, elongated field generating coil 5 which extends upwardly from near 40 the converter bottom to the line α — α which in some cases may be considered as an oil level; for example, in batch treatment. This coil 5 is made of nickel tubing and is therefore a catalyst. It also serves as an alternating 45 electric current conductor; and also as a conductor of a cooling medium, such as frigid air or cold water for example, for cooling the coil, the ends 6 of which extend outwardly through the side wall of the converter.

50 The cooling medium may be introduced at either end 6, flow through the coil and escape at the other end 6. Where the end portions of the coil 5 pass through the converter wall, they are electrically insulated from that wall 55 by passing through electric insulating blocks 7 fixed in the walls. The coil is also electrically insulated from the wall of the container by an asbestos or other suitable packing 8 between the coil and the side wall of the converter.

An alternating high frequency electric current is passed through coil 5 to energize it for the production, within and transversely of the coil, and throughout the length of the coil, 65 of a high frequency, oscillating, non-dis-

charging and consequently non-sparking electromagnetic field. The energy of this field is also exterior to the coil and through the converter wall as it is also through the metal of the coil, the supplementary catalytic cylinders mentioned below, the starting material and the vapors thereof. The oscillations in this field are of incredible velocity. Said field is effective to dissociate hydrocarbonaceous starting material into hydrogen and electrified carbon particles, these products of dissociation having a movement corresponding to that of the field in which they are generated.

70 One end of coil 5 is in electric connection, at 9, with a conductor 10 provided with a condenser 11 and a switch 11^a. Conductor 10 is in electric connection with the brush 12 of one of the two alternating electric current generating rings 13, the other ring 13 being provided with a brush 14 from which a conductor 15, provided with a condenser 16, leads into connection at 17 with the other end portion of coil 5. The electric connections with the coil, at 9 and 17, are exterior of 75 the condenser.

80 The generator rings 13 are on a shaft 18 carrying a rotor 19 and driven by an adjustable speed, electric motor 20; the rotor revolving between field pieces 21, all as usual; but, in accordance with a feature of this invention, and for effecting a constant frequency of adjusted oscillations in the high frequency, oscillating, non-discharging and non-spark- 85 ing electromagnetic field through coil 5, and consequently for treatment of the starting material in the converter chamber in such a field possessing constant high frequency of oscillations adjusted to the natural period of 90 the starting material under conversion, I 95 now provide for the alternating current circuit, a constant speed, direct current, exciter 22 driven through a power application member 23 with which the exciter is provided. Heretofore such an exciter has been mounted on the shaft 18, but I remove it from the shaft and drive it independently of the shaft and of the adjustable speed motor 20. This permits the exciter 22 to be driven at 100 105 constant speed, while the adjustable speed motor 20 may have its speed adjusted for varying the frequency of the cycles and of oscillations in the electromagnetic field; that is, adjusted at the will of the operator to vary 110 the frequency according to the particular quality or character of the material under treatment. One of the field pieces 21 for rotor 19 is in connection through a conductor 115 120 24 with the direct current exciter, at 25; and, at 26, the exciter is in electric connection with a conductor 27 which is in connection with 125 the other field piece 21.

130 The practical effect and advantage of the arrangement just described, due to the separately and constantly maintained speed of

the exciter, is to maintain electric current strength in all the oscillations of the adjusted electromagnetic field, and consequently to maintain constant frequency of oscillations and constant uniformity of treatment of the starting material and of its evolved vapor, in said field, and constant uniformity of quality of the vapor of dissociation and recombination, for each particular grade of material treated. Uniformity of the vapor results in uniformity of the quality of the hydrocarbon liquid into which the vapor is condensed. The starting material forms a working load in the electromagnetic field, and the constant oscillations in the field selected for each different kind or grade of material are advantageous in treating different grades of crude petroleum and other hydrocarbonaceous starting material, depending upon their carbon content.

In dissociating different grades or types of crude petroleum, I change the frequency of the oscillations to suit the so-called natural period of the oil or other starting material. The change in the frequency of the oscillations may be one involving a greater or less frequency than that assumed to be a normal frequency.

In all cases, according to one feature of this invention based on my discovery of its practical efficiency, the crude petroleum or other hydrocarbonaceous starting material treated for production of hydrocarbon fluid is first dissociated into a vapor by the action of the electromagnetic field in the converter chamber; the hydrogen and electrified carbon particles of the vapor then recombining into a purified vapor. Both dissociation and recombination occur in the electromagnetic field and without addition of oxygen or of hydrogen from any source extraneous to the hydrocarbonaceous starting material itself. This object, feature and economic advantage of the invention constitute an extremely important new departure from all comparable prior practice under which additional hydrogen from some extraneous source or hydrogen and oxygen have been introduced into the converter chamber and the electromagnetic field during the dissociation. The qualitative results arising from exclusion of oxygen and of hydrogen from an extraneous source are very marked in the ultimate products whether they are of high or low molecular weights. When hydrogen from an extraneous source is used on a working scale, either hydrogen gas has to be manufactured in large quantities for supplying the converter and electromagnetic field; or else, the additional hydrogen has to be supplied by dissociation of water at a high temperature sufficient to produce a supply of super-heated steam for the converter and electromagnetic field, the latter being raised to a sufficiently high heat to dissociate the

aqueous volume introduced in the presence of a catalyst into hydrogen and oxygen. Obviously, dissociation of the aqueous volume used for the additional or extraneous hydrogen supply necessarily involves supplying the converter not only with hydrogen, but also with oxygen. The oxygen does not enter into combination with the hydrocarbonaceous vapor and though some of it may be burned up in high temperature work, yet such an effect is negligible; the oxygen actively oxidizing oxidizable surfaces with which it may come into contact, and especially attacking the surfaces of the metallic catalytic elements described below or other catalytic metal in the field.

In the form shown, the supply pipe 3 communicates with the converter chamber through the converter cover 4 which is suitably fixed in place at y.

The converter chamber is provided, within the catalytic current conducting coil 5, and within the electromagnetic field, with a removable catalytic element which is preferably, but not necessarily, in the form of a plurality of concentrically arranged, spaced apart, perforated nickel cylinders 28. The cylinders are frequently perforated at 29 and are supported on insulating blocks 30 arranged on the bottom of the condenser chamber spacedly apart to permit circulation between them.

When the high frequency, oscillating, non-discharging non-sparking electromagnetic field is established, and the oil is introduced into the field, by the feed pump, if that is continuously operated, the oil is jetted or sprayed into the upper portion of the converter chamber from the discharge end of the feed pipe, upon and between the members of the catalytic elements and into the electromagnetic field. The jetting or spraying action is favorable to the almost instantly occurring subsequent dissociation. If desired, the initial oil supply may be preheated by any suitable kind of pre-heater. By the natural period of the different kinds or types of the starting material and evolved vapors is meant, as usual in physics, the inherent amplitude of vibrations peculiar to each different type.

It is during the dissociation that different impurities, often including sulphur, are released from the starting material, collecting on the converter walls and bottom, and on the walls of the members of the catalytic elements.

The dissociated hydrogen and electrified carbon particles of the recombination constitute a purified hydrocarbon vapor which passes out of the upper part of the converter chamber, in a purified and also in an expanding condition, through an eduction pipe 31 that discharges the vapor into a partial condenser 32 having two discharge ports. An

upper port is provided with a pipe 33 that delivers into a multi-stage ejector condenser member 34 which is in communication through a pipe 35 with an associated chambered condenser member 36. The tops of both members, 34 and 36, are in connection with the water supply pipe 37; member 34 being connected with pipe 37 through a valve 38 and member 36 communicating with pipe 37 through a valve 39. The member 36 is provided with a valved steam intake pipe 40. The chambered member 34 has a bottom discharge pipe 41 and member 34 has a bottom discharge pipe 42. Both pipes 41 and 42 discharge downwardly into a water separator and hot well tank 43 provided with a waste water discharge pipe 44 having a valve 45.

The partial oil condenser has a discharge pipe 46 from its under portion to a wet vacuum pump 47 for condensed oil from the partial oil condenser 32, and pump 47 delivers through an eduction pipe 48 to a fractionating manifold 49 having a gasoline delivery pipe 50 provided with a valve 51 through which the gasoline flows into a worm 52 in the gasoline condensing tank 53.

For recovery of the fugitive, light fixed gas, above mentioned and which rises from the gasoline, and for incorporation thereof as a fluid forming part of the general gasoline supply in the gasoline storage tank T, the discharge end portion 54 of the worm 52 leads into the expansion chamber of a gasoline receiver 55 above its bottom; the main portion of the gasoline flowing out of the receiver chamber through an eduction pipe 56 that discharges into the gasoline storage tank T. But the exceedingly light and economically important fugitive gas expandingly and continuously rises from the body of the gasoline and flows through the receiver chamber and out of it through a pipe 57 into the chamber of a second converter 58 in which the light fugitive fixed gas is converted into fluid gasoline which flows out through a pipe 59 into the gasoline storage tank T.

The converter 58 may be either of metal with an interior field generating coil as above described; or it may be of dielectric material, if preferred. The coil 60 is in circuit through leads 61 and 62 with the conductors 11 and 15 through which coil 5 is energized. Converter 60 is shown provided with the catalytic metal cylinders 28. Apparatus for the purposes described may be made largely of ceramic material when economy of plant construction is desired.

Substantially better results are obtained for liquefaction of the fixed gas introduced into converter 58, and subjection therein to the action of the high frequency, oscillating, non-discharging and non-sparking electromagnetic field, by winding the coil 5 clockwise and the coil 60 anti-clockwise as shown. The opposite sides of the perforated plate P

or screen of catalytic metal; the opposite end portions of the catalytic metal tubes 28 and the ends of the interior conducting coil of catalytic metal act as poles. The alternating current generator driven at a variable speed and in circuit as described with the constant speed direct current exciter produces a constant magnetic field in the generator when the generator speed is varied. The variations in the speed of the generator create variations in the frequencies without changing either the strength of the alternating field or the voltage of the exciter; and the catalytic metal pole-forming portions are alternately polarized, thus alternately subjecting the starting material to polarizing effects. I have found in practice that the winding of the coils in reverse directions has a new effect on the catalytic, electrically energized members that is quite different from the effect obtained when the coils are both wound in the same direction. The coils wound in reverse directions as shown are connected in series and are wound clockwise and anti-clockwise in order to vary the magnetic fields produced in the catalytic metal members, severally, and analogously to the field variations obtained by winding electromagnets in direct current work for production of north and south poles; the so-oppo- sitely wound coils effecting the opposite polarities, act and re-act on the catalysts and on the carbon content of the starting material under treatment. I find that this action and re-action positively intensifies the con- joint action of the catalysts and energized carbon particles and that the polarization of the catalytic material is a highly important feature of my invention.

The converter 4 has a bottom discharge pipe 63 for carrying off the impurities or sludge. It leads to the intake side of a wet vacuum pump 64 which discharges through its eduction pipe 65 into a sludge residue tank T'.

When and if the apparatus is to be operated for production of lubricating oil, it is desirable to put a booster ejector into operation ahead of the vacuum apparatus described, if that is used; or ahead of the fractionating manifold, as the case may be. Such a booster ejector is shown and includes a chambered member 66 provided at one end with a high pressure steam supply pipe 67 which delivers steam into the chamber of member 66 crosswise of the upflow of vapor of recombination from converter 4 through pipe 31. This ejector member 66 is inter-posed, conduitwise, in the pipe 31, the dis-charge from member 66 being through a por- tion of the pipe 31. If the ejector booster member is used, the hydrocarbonaceous va- por ascending into the booster member is en- trained by the high pressure steam.

As above stated, the Fig. 1 structure is

convertible and may be used for high, low or intermediate pressure operation.

To shut off the booster ejector, a valve A with which the high pressure steam supply pipe is provided, is closed. The booster ejector structure then becomes merely a portion of the conduit connection of converter 4 with a partial vacuum apparatus designated by the reference numerals 32 to 48, inclusive.

10 To shut off the partial vacuum apparatus, a valve B in pipe 31, forward of the oil partial condenser 32, is closed; the vapor of recombination then passing directly to the fractionating manifold 49 through a by-pass 15 pipe 68 between pipe 31 and the fractionating manifold 49.

The sludge discharge pipe 63 is provided with a shut-off valve C and feed pump education pipe 3 is provided with a shut-off valve 20 D. With the valve C closed, the feed pump may be operated slowly to supply converter 4 with a batch of starting material up to the level α — α , valve D being then closed. Various other valves may be supplied for convenience in adapting the apparatus to various working conditions.

The fractionating manifold 49 is provided as usual with valve take-off pipe such as 68 for kerosene; 69 for gas oil and 70 for lubricating oil.

Converter 4 is provided with an automatic pressure relief valve E in communication with the chamber of converter 4 through a pipe 71. The automatic relief valve remains closed during partial vacuum operations.

Converter 4 is also provided with a flue 72 provided with a shut-off valve 73. The flue is used only when the converter is to be cleaned out by raising the temperature of 40 said field and burning sludge and other impurities off interior surfaces of and within the converter chamber.

By using sections of catalytic metal cylinders concentric and removably mounted in 45 the chamber of converter 4, it is possible conveniently to vary the area of catalytic surface to which the starting material, the vapor of dissociation and the vapor of recombination are exposed during operation.

50 The coil 5 under the conditions stated being located within the converter chamber and electrically insulated from the walls of the converter 4, affords some resistance to the alternating electric current of which it is a conductor and tends to become more or less heated by self-induction. This coil 5 is in circuit with the high frequency alternating electric current generating means; and I have discovered that the catalyst is rendered more intensive in its catalytic action when electrically energized than is otherwise the case. The catalytic cylinder sections are within the coil and their temperature is naturally raised to a greater or lesser degree by induction from the electromagnetic field.

In case the temperature of the coil 5 due to its resistance to the current is greater than desired, the coil temperature is reduced by passage of the cooling media through it. If a higher heat is desired, the current strength 70 is increased. Reduction of heat in the coil 5 is more particularly secured by reduction of the speed of the alternating current generator. The use of the cooling media such as cold water or frigid air is a convenient way 75 of generally reducing too great a temperature in the coils. Reduction of current strength in the coils by reduction of the speed of the alternating current generator constitutes the practical way of obtaining a low temperature 80 of the converter structure in whole and in part.

I have found it very desirable not only for safety and convenience but also for increased 85 quantitative and qualitative results in the distillation of some grades of crude petroleum, to operate at substantially low temperatures; for example, at from about 75 degrees Fahrenheit up to about 250 degrees Fahrenheit. Production of motor fuels and the like at 90 any of such low temperatures has been hitherto unheard of in the art; and just as the dissociation and recombination above referred to, without addition of oxygen or of hydrogen, constitutes a new departure in the 95 art; so my present low temperature distillation constitutes a new departure, and it has the great advantages of safety and convenience because the converter in its general structure is kept approximately cool and 100 workmen are not liable to be burned or otherwise injured by contact with the coil or converter wall. Moreover, my invention secures freedom from explosions and substantially increased quantitative and qualitative 105 results.

By operating the charging pump at speed the starting material will issue as a spray into the upper portion of the chamber of converter 4. As the oily spray descends, counter 110 currentwise to the ascent of the generated and recombined vapors, it passes into the electromagnetic field and is immediately dissociated. Simultaneously, sulphur and other 115 impurities are separated from the vapors of dissociation, and are best removed continuously away from the presence of the dissociating and recombining constituents of the vapors by operation of the pump 64 or by unaided, outflowing discharge through the 120 pipe 63. The molecular weight of the starting material is reduced during dissociation and recombination by elimination of the various impurities referred to including the mysterious waxy substance above mentioned.

When the higher partial vacua are required than above indicated, and such as correspond to an absolute pressure of approximately fifteen millimeters of mercury, such vacua may be obtained by operation of the 125

steam jet type of booster ejector above described; but whatever degree of partial vacuum is required may be obtained by use of any other practical form of partial vacuumizing apparatus.

As in some cases it may be preferred to install a pressure system as a unit without association with partial vacuum apparatus, I have shown in Fig. 2 a pressure system which is the same as the pressure system as shown in Fig. 1. But in the Fig. 2 construction, the sludge discharge pipe 63 leads directly to the pipe 65 through the shut-off valve 64^a which takes the place of the wet vacuum pump 64 shown in Fig. 1. In both Figs. 1 and 2, I show a transverse perforated, nickel and therefore catalytic, baffle plate P the periphery of which is detachably secured in the insulating mat M interposed between the converter wall and the interiorly mounted coil. By making the baffle plate P detachable, access is had to the removable catalytic cylinders for varying the number thereof to suit working conditions. Plate P is merely forced peripherally into the mat and is electrically energized by induction from the electromagnetic field.

Whenever desired, and without departure from the broader features of this invention, the converter may be of dielectric ceramic material, and in that case the alternating current conducting coil may be either inside or outside the converter chamber; said chamber may be interiorly provided with or may not be provided with a catalyst; and hydrogen from an extraneous source may be introduced into the converter chamber. With some grades of material or under some circumstances, hydrogenation may be desired and be beneficial as explained in my prior patents. In Figs. 1 and 2, I show a hydrogen intake pipe 76 provided with a shut-off and regulating valve 77, this hydrogen supply pipe discharging into the converter chamber for the starting material or otherwise as may be preferred. By closing valve 77 no hydrogen will be admitted.

The booster ejector 66 when used assists in propelling heavy gases through the vapor pipes commonly called vapor lines. Operation of ejector 66 effects higher vacua which increase the flowing movement of the heavy gases through the vapor lines.

By increasing the frequency of the current through the coil the function of which, as already stated, is to establish a high frequency, oscillating, non-discharging, non-sparking electromagnetic field within the coil and converter chamber, a distillate of heavier molecular weight, such as lubricating oil, is obtainable.

The temperatures in the converter chamber when there is an electric resistance in the electromagnetic field may be varied to any degree from about 50 degrees Fahrenheit to

1500 degrees Fahrenheit, or more, by regulation of the electric current; and the pressures may be varied from below atmospheric to about 2000 pounds per square inch or more by adjustment of the automatic pressure relief or safety valve with which the converter chamber is provided. It is, however, a demonstrated fact that temperatures are of relatively and generally of slight importance in the described operations which are effected mainly, if not in most cases exclusively, by change of frequencies to which questions of temperature are incidental.

Converter 4 may be called the initial converter and converter 58 may be called the light gas converter.

A cylinder 28 in both converters, together with the plates, P, shown in each converter function as short-circuited secondaries and can be replaced if so desired by constant graphite and carbon, with or without catalytic metal pieces, all as described in my Letters Patent aforesaid, and if preferred, they can be replaced by natural metallic ores such as iron ores, galena, nickel or copper, for example. In large scale operations the use of natural ores as catalysts and short-circuited secondaries will be economically advantageous.

The gaseous vapors generated may involve high, internal pressure in the converter chambers and an automatic pressure relief valve E, or the like, which can be set at any desired pressure is very desirable to permit safe operation at very high pressure. As shown, the Fig. 1 apparatus can be used at pressures below atmospheric and at a great range of pressures above atmospheric, from low to very high. Even a converter of dielectric material may be used for very high internal gaseous pressures with such a relief valve. When working with high pressures and with the valve P or E open, any undue high pressure would be relieved to a considerable extent through the sludge escape pipe 63. Nevertheless there is generally no practical reason for working at anything approximating high pressures. Generally the work described has been found to be most effective under low pressure or partial vacuum conditions.

In Figs. 1 and 2 the cylinder or tube sections 28 of catalytic material, preferably nickel, are in the electromagnetic field and are energized inductively by it. While I show a plurality of these sections 28 with passages between them for flow and treatment of the starting material, they may be reduced in number. A single tube or section 28 within the field may be used. Whether one or more of these catalytic tubes or sections are employed, they are in substance and effect a part of the converter structure, being active in the disassociation and vaporization of the starting material. chamber of the converter 4 forms an expansion chamber. Various changes in the form of construction of the converter structure may be made without departing from the principle of the invention. Thus in Fig. 4, the oil suction line 3; the pressure relief valve E; the valved flue 72; and the vapor escape conduit 31 and the provisional hydrogen supply pipe 76 are all entrant into a chambered header or manifold 80 which forms an expansion and mixing structure; the manifold 80 being provided with a plurality of depending tubes 81 the under ends of which communicate with a chambered header 83 from which the sludge removing apparatus including pipe 63 is in communication. The manifold 80; the tubes 81 and the manifold 83 are preferably of catalytic material such as nickel. The tubes 81 are all enclosed within the energizable coil 82 for establishment of the high frequency, oscillating, non-discharging electromagnetic field.

In Fig. 5 only one tube 81 is provided for the header or manifold 80 this tube being enclosed by the electromagnetic field generating coil 82 and the under end of the single tube 81 being in communication with the sludge removing apparatus through pipe 63. In the Fig. 5 structure the manifold 80 and the single tube 81 are both preferably of catalytic metal such as nickel. The converter 4 is practically a tube with openings at its upper end and an opening at its under end.

Having described the principle of this invention and shown different forms of apparatus embodying the principle and useful in practicing my new method, and intending to cover all features of the invention in the broadest, legally permissible manner.

40. **What I claim is:**

1. The combination with a chambered converter and alternating, electric current conducting coil effective to establish through the coil and within the converter chamber, a high frequency, oscillating, non-discharging and non-sparking electromagnetic field of an alternating current generator with which the coil is in circuit; the converter and coil being each made of any appropriate material and the coil being located either outside or inside the converter chamber; vapor condensing apparatus in conduit connection with the converter chamber; a receiver in conduit connection with the vapor condensing apparatus; for reception of a condensed distillate; a storage tank in conduit connection with the receiver; a light weight, fugitive gas converter in conduit connection with the receiver and having a chamber in conduit connection with the tank.

2. The combination with a chambered converter for initial treatment of starting materials, and an alternating, electric current conducting coil effective to establish through the coil and within the converter chamber,

10. a high frequency, oscillating, non-discharging and non-sparking electromagnetic field; of partial vacuumizing apparatus having its intake side in conduit connection with the chamber of said converter; the vacuumizing apparatus including a vacuum pump for discharge of a condensate; condensing apparatus into which the said pump discharges; a receiver in conduit communication with the condensing apparatus; a tank in conduit communication with the receiver; and a light weight, fugitive gas converter having a chamber in conduit connection with said tank, and provided with an energizable, alternating electric current conducting coil for establishing a high frequency, oscillating, non-discharging and non-sparking electromagnetic field within the chamber of the last mentioned converter.

3. The combination with a chambered converter for initial treatment of starting materials, and an alternating, electric current conducting coil effective to establish through the coil and within the converter chamber, a high frequency, oscillating, non-discharging and non-sparking electromagnetic field; of partial vacuumizing apparatus having its intake side in conduit connection with the chamber of said converter; the vacuumizing apparatus including a vacuum pump for discharge of a condensate; a condenser with which the eduction side of said pump is in conduit communication; and a bypass conduit in conduit communication with the converter chamber; and means under the control of an operator for rendering the partial vacuumizing apparatus ineffective, thereby permitting the apparatus to be used at pressures at or about atmospheric; and for rendering the bypass conduit inoperative when the apparatus is to be used under partial vacuum conditions.

4. The combination of a chambered converter, the converter having an intake port for starting material and an escape port for a product of treatment, and also having spaced apart from said intake and escape ports, a sludge discharge port; a high frequency, alternating, electric current conducting coil, electrically insulated from the converter and arranged for electrical connection with a source of high frequency, alternating electric current for generation within the coil and converter chamber of a high frequency, oscillating, non-discharging and non-sparking electromagnetic field; said coil being of catalytic metal.

5. The combination of a chambered converter; an energizable, high frequency, alternating, electric current conducting coil therefor effective to establish in the converter chamber, a high frequency, oscillating, non-discharging, non-sparking electromagnetic field; and, within the converter chamber, a

- series of removable, frequently perforated, open ended cylinders of catalytic metal.
6. The combination of a chambered converter; an energizable, high frequency, alternating electric current conducting coil therefor effective to establish in the converter chamber, a high frequency, oscillating, non-discharging, non-sparking electromagnetic field; and, within the converter chamber, a series of removable, frequently perforated, open ended cylinders of catalytic material; the coil being within the converter chamber, of catalytic metal and out of electric contact with the converter wall; the converter wall being of steel or other metal of high tensile strength.
7. In the combination set forth in claim 6, a transverse, catalytic metal, perforated plate; and electric insulating means therefor; the plate being removably installed and energizable by induction from said field.
8. The herein described method of converting petroleum oil and other starting material into fluids of changed molecular weight, consisting in spraying the starting material counter-current-wise to the outflow of generated hydrocarbon vapors into a place of partial confinement adjacent a high frequency, oscillating, non-discharging, non-sparkable electromagnetic field, simultaneously expanding the spray, passing it into said field, and therein and thereby dissociating it into hydrogen and electrified carbon particles; recombining the hydrogen and electrified carbon particles; passing the vapor of recombination out of the place of formation in a direction opposed to the direction of the spray; and in simultaneously removing impurities from the starting material and vapors and passing the same out of the place of vaporization counter-current-wise to the path of discharge of the purified vapor.
9. The herein described method of converting petroleum oil and other starting material into fluids of changed molecular weight, consisting in subjecting the starting material to the action of a high frequency, oscillating, non-discharging and non-sparkable electromagnetic field, therein and thereby dissociating the hydrogen and carbon of the starting material, and electrifying the carbon particles; during the dissociation, removing impurities from the starting material and from the hydrocarbonaceous vapor of dissociation; and in recombining the hydrogen and electrified carbon particles of the dissociation into a purified hydrocarbonaceous vapor; expanding the same and passing it from the place of dissociation, purification and recombination; and in simultaneously and continuously removing sludge from the place of dissociation and purification.
10. The combination of a chambered converter; an energizable, high frequency, alter-
- nating, electric current conducting coil enclosing the converter and effective to establish therein, a high frequency, oscillating, non-discharging, non-sparking electromagnetic field; the converter walls being of catalytic metal; the converter being formed with a chamber for expansion and mixing of vapors and with one or more tubes also of catalytic metal enclosed by the coil.
11. The combination of a chambered converter having a metal wall; an insulation mat around the interior of the metal wall; an energizable electromagnetic field generating coil within the converter chamber and separated from the metal wall by the mat; the ends of the coil projecting outwardly through the converter wall and being electrically insulated therefrom.
12. The combination of a chamber-converter; an energizable, high-frequency, alternating electric-current conducting coil effective to establish in the converter chamber a high-frequency, oscillating, non-discharging, non-sparking electromagnetic field; the converter walls being of catalytic metal and the converter being formed with a chamber for expansion and mixing of vapors and with one or more tubes of catalytic metal mounted in said field.
13. The combination with a container for hydro-carbon starting material; an alternating current conducting coil, effective for production of a high-frequency, oscillating, non-sparking, electromagnetic field within the container chamber; a polarizable, catalytic member in said electromagnetic field; of a chambered vapor-receiver in conduit connection with the container chamber; and an alternating, current conducting coil for the vapor receiver effective to produce therein a high-frequency, oscillating, non-sparking, electromagnetic field; a polarizable catalytic member in the electromagnetic field in the receiver chamber; said coils being reversely wound and in series, thereby to effect alternate polarization of said catalytic members for intensification of the catalytic action thereof.
14. In apparatus for treatment of hydrocarbons and other material, the combination with a high frequency, oscillating, electromagnetic field inducing coil; of an alternating current generator; a variable speed motor for driving the generator; conductors connecting the coil with the generator; and a constant speed direct current exciter; and conductors connecting the exciter with the field pieces; whereby the exciter may be driven at constant speed and the motor may be given an adjusted speed for varying the frequency of the cycles and of oscillations in the electromagnetic field for maintenance of current strength of the oscillations in the adjusted electromagnetic field, constant fre-

quency of oscillations, and uniformity of treatment.

15. In apparatus for treatment of hydrocarbons and other materials, the combination with a high frequency, oscillating, electromagnetic field inducing coil; of an alternating current generator; a variable speed motor for driving the generator; conductors connecting the coil with the generator; and 10 a constant speed direct current exciter; and conductors connecting the exciter with the field pieces; whereby the exciter may be driven at constant speed and the motor may be given an adjusted speed for varying the 15 frequency of the cycles and of oscillations in the electromagnetic field for maintenance of current strength of the oscillations in the adjusted electromagnetic field, constant frequency of oscillations, and uniformity of 20 treatment; and another electromagnetic field inducing coil in circuit with the conductors between the generator and the first mentioned coil; the coils being wound in reverse directions.

25. 16. The herein described method of treating hydrocarbons, consisting in vaporizing a hydrocarbon, such as petroleum oil or vapor in a high frequency, oscillating electromagnetic field; passing and condensing the 30 vapor into a main stream of lighter weight petroleum oil; passing such main stream to a place of reception; capturing light weight vapor arising from the main stream; passing the captured vapors through a high-frequency, oscillating electromagnetic field; liquefying the captured vapors in this latter field; and passing the so liquefied vapors to a 35 place of recovery.

40. 17. The herein described method of converting petroleum oil or vapor and other starting material into fluids of changed molecular weight, consisting in spraying the starting material counter-current-wise to the outflow of generated vapors into a place of 45 partial confinement adjacent an oscillating electromagnetic field; adjusting the frequencies of electric impulses in said field to the requirements of the particular starting material under treatment; expanding the spray 50 and passing it into said field, therein and thereby dissociating the spray, and passing the vapor so formed out of the place of vaporization counter-current-wise to the 55 path of discharge of the vapor.

60. 18. The herein described method of treating hydrocarbons, consisting in vaporizing a hydrocarbon in an electromagnetic field; passing and condensing the vapor into a main stream of a liquid hydrocarbon; passing such main stream to a place of reception; capturing vapor arising from the main stream; passing the captured vapor arising from the main stream through another electromagnetic field; liquefying the captured 65

vapor in the latter field, and recovering such liquid.

19. The herein described combination of an electromagnetic field generating apparatus; a receptacle for vaporizable material to be 70 treated located in said field and under the influence thereof; a vapor eduction conduit from the receptacle; a vapor condenser; a main eduction conduit from said condenser; a secondary vapor eduction conduit from the 75 main eduction conduit from the condenser; a second electromagnetic field generating apparatus and receptacle located within the influence of the second field; the secondary conduit discharging into the receptacle under the influence of the second field. 80

20. The herein described method of making anti-knock gasoline, consisting in vaporizing petroleum oil or vapor in an electromagnetic field at a temperature of from 85 about 75° to about 400° Fahr. and at approximately atmospheric pressure or lower; in condensing the vapor into gasoline and passing the same as a main stream to a place of reception; in capturing light weight vapors 90 arising from such main stream and passing them through another electromagnetic field therein and thereby converting the captive vapors into gasoline; and in recovering the converted vapor gasoline. 95

21. In apparatus of the class described, the combination of a converter; an electromagnetic field inducing coil therefor; and a frequently orificed transverse vapor baffling member of catalytic metal located in the converter chamber with its edge closely adjacent the converter wall near the coil; such member being within the influence of said field and thereby energizable. 100

22. The combination of a metal walled vaporizer, an insulating side lining for the vaporizer chamber, and an electromagnetic field generating coil of catalytic material located within the insulated side wall lining thereby reducing the field energy outside the 110 vaporizer. 105

Signed at New York in the county of New York and State of New York this 8th day of August A. D. 1929.
